Fig. 7

Fig. 8

FIG. 1 is a top plan view of a cabinet for telecommunication and sound reproduction equipment showing one form of my new design;

FIG. 2 is a front view of the form shown in FIG. 1;

FIG. 3 is a side view of the right side of the form shown in FIG. 1, the opposite side being substantially a mirror image thereof;

FIG. 4 is a front perspective view of the form shown in FIG. 1;

FIG. 5 is a top plan view of a cabinet for telecommunication and sound reproduction equipment showing modified form of my new design;

FIG. 6 is a front view of the form shown in FIG. 5;

FIG. 7 is a side view of the right side of the form shown in FIG. 5, the opposite side being substantially a mirror image thereof;

FIG. 8 is a front perspective view of the form shown in FIG. 5.

This application is a continuation of my copending applications, Ser. Nos. D. 14,320, filed Nov. 5, 1968, and D. 14,325, filed Nov. 5, 1968, now abandoned.

I claim:

The ornamental design for a cabinet for telecommunication and sound reproduction equipment, substantially as shown and described.
